(57) **CLAIM**

The ornamental design for a graphic user interface for a portion of a display screen, as shown and described.

DESCRIPTION

The FIGURE is a front view of a graphic user interface for a portion of a display screen showing our new design.

The broken line showing of a region and the unshaded area there within forms no part of the claimed design. The broken line showing a portion of a display screen and text is for illustrative purposes only and forms no part of the claimed design.
